UNITED STATES PATENT OFFICE.

CHARLES D. YOUNG, OF PHILADELPHIA, PENNSYLVANIA.

JOINT BAR.

Application filed May 25, 1921. Serial No. 472,563.

To all whom it may concern:

Be it known that I, CHARLES D. YOUNG, a citizen of the United States, residing at Philadelphia, in the county of Philadelphia and State of Pennsylvania, have invented 5 certain new and useful Improvements in Joint Bars, of which the following is a specification.

My invention relates to joint bars or fish- 10 plates for rail joints, and one of the objects is to make such joint bars stronger and more durable than heretofore.

Another object is to provide an improved 15 bar which secures all of the advantages of the so-called "continuous" type of bar but which is of minimum size and mass and is not characterized by certain objections incident to standard forms of "continuous" bars.

Still another object of my invention is to 20 provide an improved bar which in service is not subjected to reverse bending stresses during wheel passage over the last half of a joint.

How these and other advantages can be 25 secured through my invention will appear from the following description of the best form of embodiment at present known to me.

In the drawings, Fig. 1 is a side elevation 30 of a joint having a bar embodying my invention; Fig. 2 is a plan view of Fig. 1; Fig. 3 shows a transverse section through a rail and bar applied thereto, taken as indicated by the line 3—3 in Fig. 1; Fig. 4 is a fragmentary side view, partly in section, taken as indicated by the line 4—4 in Fig. 3; Fig. 5 shows a transverse section through a modification of the bar of Fig. 4 in place; Fig. 6 shows a transverse section through 40 another form of bar; and Fig. 7 is a fragmentary side elevation of still another modified form of bar.

The bar shown in Figs. 1 to 4 comprises 45 a web 10 having a laterally enlarged head or upper flange portion 11 and a laterally enlarged or extended base, foot, or lower flange portion 12.

The head and foot portions 11 and 12 are 50 appropriately beveled for engaging between and with the lower and upper surfaces of the rail head 13 and base 14. As shown, the head and foot portions 11 and 12 are appropriately varied in cross section to dis- 55 tribute the fiber stress substantially uni-

formly from end to end of the bar, in a manner described in my copending application Serial No. 466,081 filed May 2, 1921. The mass and the vertical thickness of the head 11 and the foot 12 are greatest at the middle 60 of the bar, and diminish gradually toward the ends of the bar. The cross-section and horizontal width of the foot 12 are greatly increased at 15 in the middle third of the bar, yet without abrupt change. The wide 65 portion 15 is extended laterally beyond the edge of the rail base, then turns downward as a hanging flange, and then extends laterally outward again. As shown, these variations of dimensions and cross-section are 70 such as to distribute the effects of the load substantially uniformly throughout the length of the bar, so as to avoid localization of fibre stress and make such stress substantially uniform, under deflection, from end to 75 end of the bar. This allows the bar to be made as light as possible, and thus reduces the mass and momentum of the whole joint when it rebounds after depression and elastic deflection of the rail by a passing wheel, and minimizes the vibration and the hammering effects.

In addition to the features described, the bar has an extension 16 of its foot portion 12 inward beneath and engaging the lower 80 sides of the bases 14, 14 of the meeting rail sections or lengths at their junction, in the region of the extreme lateral extension 15. As shown in Fig. 2, this inward extension 16 is relatively narrow, and has the form of 85 a triangle with its apex in the line or plane of meeting of the rail ends, close to the vertical central plane of the rails. About in the plane of the meeting rail ends are transverse webs or flanges 18, 19, 20 by means of 90 which the web 10, the bend 21 at the extremity of the extended foot portion 15, and the inward extension 16 are reinforced 95 against deformation under the stresses due to the wheel load and the passage of the 100 wheels over the rails. The upper surface of the inward extension 16, the bottom of the groove between the parts 15 and 16, and the lower surface of the part 15 are all eased or 105 hollowed out at 22 about the outer portion 105 of the rail base 14, to afford "breathing space" at this point and confine the transmission of stresses between the rail bases 110 and the bar to the inner portion of the base 14. In the case of the part 12, the breath-

ing space extends clear across it, and is thus coextensive, transversely of the bar, with its overlap with the rail base in the middle region of the bar, as indicated at 23 in Figs. 5 3, 4, and 5, etc.

The purpose of this breathing space is to relieve the bars of reverse bending during the latter portion of wheel passage over the joint. For example, if the leading wheels 10 of a truck are past the joint and the rear wheels are on the last half of the joint, the rail is bent in a reverse arc which tends to bend the joint bars in an arc the reverse of that to which they are bent or deflected 15 when the truck wheels reach the joint. The latter deflection cannot be avoided but the additional reverse bending seriously affects the bars and rapidly produces strains and resultant breakages, particularly at the bolt 20 holes. By the provision of this breathing space, the rail end is left free to take the reverse bend without imparting a similar bend to the bar. The relative narrowness of the extension 16 lengthwise of the bar economizes 25 metal, and may in some cases also help to obviate undesirable stressing of the bar. The reverse bending of the bar is thus largely, if not wholly eliminated, and its life correspondingly increased.

30 In the form of bar shown in Fig. 7, the flanges 18 reinforcing the web 10 is in the plane of the meeting rail ends, but the flanges 19 and 20 of Figs. 1 and 2 are replaced by duplicate reinforcing webs or flanges 19^a, 19^b, and 20^a, 20^b at either side of 35 the plane of the meeting rail-ends.

In the modification shown in Fig. 6, reinforcement of the bar web 10 is dispensed with altogether, though the bend 21 and the 40 inward extension 16 are reinforced with flanges 19^a, 20^a.

45 My bar can be made by forging or other methods and when forged, the plane of parting of dies employed is indicated by the line 25—25 in Fig. 3. When the bar is thus die-pressed, however, the dies are made to give the part 16 the form and position indicated in dotted lines at 16^a in Fig. 3, in order that it may be possible to remove the piece from 50 the dies. The part 16 is bent to its full-line position in a separate operation after removal from the dies.

I claim:

1. A rail joint bar comprising a web with head and foot portions for engaging between the heads and the bases of the meeting rail lengths, and a relatively narrow extension of the foot for engaging beneath the base of the rail lengths at their junction, said foot portion having a breathing space above the rail base in the middle region of the bar coextensive with its overlap with said base transversely of the bar, and extending over the whole of said extension. 55

2. A rail joint bar comprising a web with head and foot portions adapted to engage between and against the heads and the bases of the meeting rail lengths at the ends of the bar, and a relatively narrow extension on the foot for engaging beneath the bases of the rail lengths at their junction, said foot portion having a breathing space above the rail base coextensive with its overlap with the latter, transversely of the bar, and extending to either side beyond said extension. 60 70 75

3. A rail joint bar comprising a web with head and base portions adapted to engage between those of the meeting rails, the mass and cross-section of the bar diminishing gradually at either side from its middle in 80 such wise as to make the fiber stress in service substantially uniform throughout the length of the bar, with an extension of the base of the bar beneath the bases of the rail lengths at the middle of the bar only. 85

4. A rail joint bar comprising a web with head and base portions adapted to engage between those of the meeting rails, the mass and cross-section of the bar diminishing gradually at either side from its middle in 90 such wise as to make the fiber stress in service substantially uniform throughout the length of the bar, with an extension of the base of the bar beneath the bases of the rail lengths, the base portion of the bar having a breathing space above the rail base coextensive with its overlap with the latter, transversely of the bar, and extending over the whole of the aforesaid extension. 95

100 In testimony whereof, I have hereunto signed my name.

CHARLES D. YOUNG.
